FIG. 5.

FIG. 6.

FIG. 10. James M. Mc Kee
By John Boyle Jr. *MM*

UNITED STATES PATENT OFFICE.

JAMES M. MCKEE, OF NEW BLOOMFIELD, PENNSYLVANIA.

LOCK.

1,382,924.

Specification of Letters Patent. Patented June 28, 1921.

Application filed October 6, 1920. Serial No. 414,978.

To all whom it may concern:

Be it known that I, JAMES M. MCKEE, citizen of the United States, residing at New Bloomfield, in the county of Perry and State 5 of Pennsylvania, have invented certain new and useful Improvements in Locks, of which the following is a specification.

My invention relates to locks, and one of the objects of the invention is to provide a 10 lock which cannot be easily picked and which can not be unlocked by a master key.

Another object of the invention is to so design the operative parts of the lock, that by variation in the location or size of these 15 parts, a wide number of different combinations may be effected in which no two keys will be alike or operate the same lock.

Another object of the invention is in the application of this lock to safeguard automobiles against theft, by locking the steering wheel, spark and gas levers against unauthorized movement; also for locking tires, robes and other articles in the automobile.

Another application of my invention is for 25 locking the steering post against turning, thus preventing theft of a machine by towing.

With these general objects in view, my invention consists in certain novel and peculiar 30 features of construction and combination of parts as hereinafter described and claimed, and in order that it may be fully understood, reference is to be had to the accompanying drawing in which—

35 Figure 1 is a perspective view of the lock as constructed for locking the steering wheel spark and gas levers against movement or for locking articles in the machine, such as robes;

40 Fig. 2 is a plan view of the same with the cover open and showing the operating parts of the inner lock;

Fig. 3 is a longitudinal section on the line 3—3 of Fig. 2;

45 Fig. 4 is a transverse section on the line 4—4 of Fig. 3;

Fig. 5 is an enlarged transverse section of the line 5—5 of Fig. 3;

50 Fig. 6 is an enlarged transverse section on the line 6—6 of Fig. 3.

Fig. 7 is a detail view of the sliding bolt of the inner lock;

Fig. 8 is a detail view of the key for the lock;

55 Figs. 9 and 10 are detail views of a modification of the locking chain.

Referring to the drawings 1 is a box like receptacle or casing having a cover 2 connected thereto by hinges 3. Within the casing 1 is a locking member 4 comprising a 60 slideable bolt 5 which engages with a member 6 carried by the cover 2 and holds the said cover in closed and locked position as shown in Fig. 1. On each side of the casing are slots 7 and in the bottom of the slots are 65 spring catches 8 for coöoperating with ratchet bars 9 that are adapted to slide into different adjusted positions and to be held against movement in one direction by the said catches. Connected to the end of the 70 ratchet bars and to the bottom of the casing to provide a loop, are the chains 10.

The locking member 4 is provided with a reciprocating U shaped pin 11 which is normally forced forward by the leaf spring 12. 75 The end 13 of the pin 11 when in forward position, engages an aperture 14 in the bolt 5, while the other end 15 projects a short distance into the keyhole 16. For resiliently holding the sliding bolt 5 in locked position, a spring 17 is provided. The under side of the sliding bolt 5 is provided with rack teeth 18 which engage with the pinion shaped body 19 of the key 20. The said key is provided with an arbor 21 which fits the bearing 22 80 in the bottom of the keyhole 23. On the end of the pinion 19 is a pin 24 which when the key is inserted in the keyhole alines with and abuts the projecting end 15 of the pin 11. As the key is pressed forward the pin 11 is 85 forced rearwardly against the pressure of the spring 12 and the end 13 of the said pin is withdrawn from the aperture 14. As the key is turned, the coöperation of the rack 18 with the pinion 19 will reciprocate the locking bolt 5. In order that the key shall not move forward when inserted, so far as to cause the pin 24 to enter the aperture in which the end 15 of the pin 11 slides, a limiting stop 25 is provided in the bottom of the 90 keyhole. For causing the key to enter the slot in a predetermined position, I provide a spline 26 in the keyhole, and coöoperating with a groove 27 in the key. To prevent rotation of the bolt 5, the said bolt is provided 95 with a slot 28 with which the slightly projecting end 13 of the locking pin coöperates when in retracted position.

The operation of my invention is as follows: The cover 2 of the receptacle is in 110 locked position. If it is desired to lock the spark and gas levers of an automobile, the

chain is looped around them in such a manner as to prevent movement thereof, and the rack bars 9 are then inserted in the slot 7 and pushed forward until the loops of the 5 chain are taut. The coöperation of the spring 8 and the rack bars prevent withdrawal of the latter. When it is desired to unlock the device, the key is inserted in the keyhole properly by the coöperation of the 10 spline 26 and groove 27. As the key is pushed forward into position, the locking pin 11 is retracted so that the bolt 5 is free to slide, which it is caused to do through the coöperation of the rack 18 and pinion 15 19. The cover 2 can then be raised and the rack bars 9 withdrawn. In locking the cover in closed position the reverse sequence of operations takes place.

From the description above given it will 20 be seen that it is difficult to pick this lock or to make a master key therefor on account of the several factors which must co-operate in order that the lock shall operate.

A large number of different combinations 25 may be effected by changing the disposition of the teeth in the rack and pinion on the bolt and key; by changing the location of the spline and groove on the keyhole, and by changing the length of the projecting 30 end of the locking pin. Such a variation of combinations permits of the use of a large number of keys, none of which are duplicates.

Instead of using the chain as shown in 35 Fig. 1 a block chain as shown in Figs. 9 and 10 may be used. The advantages of this type of the chain is that a smaller loop can be made as the chain itself can be drawn through the grooves 7 and locked in position.

From the above description it will be apparent that in the application of my invention as illustrated, the device as shown is essentially a lock within a lock. It is intended however that the inner locking member shall be of general application. One of the other uses to which it may be put is in connection with locking the steering gear of an automobile. In that case the body of 50 the lock would be placed on the steering casing and the bolt would enter the aperture in the steering post, thus preventing relative rotation of these two parts.

From the above description it will be apparent that I have produced a device of the 55 character described, which possesses all the features enumerated as desirable, and while I have illustrated and described the preferred form of the invention, it will be understood that I reserve the right to all changes properly falling within the spirit and scope of the appended claims.

Therefore what I claim as new and desire

to secure by Letters Patent of the United States is:

1. A lock comprising a bolt and a plural-armed locking pin, one arm of the said pin coöoperating with the said bolt to lock it against movement, a key adapted to co-operate with the other arm to release the 70 first named arm from engagement with the bolt and coöperating means on the key and bolt for moving the latter when the key is turned.

2. A chain lock comprising a casing member, a cover member hinged thereto, one of the said members being slotted, flexible securing means attached at one end to one of the said members and at the other end provided with means for engaging the slotted 80 member, and means for locking the cover member to the casing member to lock the flexible securing means in position.

3. A lock comprising a bolt and a U shaped locking pin, one arm of the said pin 85 engaging with the bolt to lock it against movement, a key adapted to coöperate with the other arm to release the first named arm from engagement with the bolt and co-operating means on the key and bolt for 90 moving the latter when the key is turned.

4. A lock comprising a bolt and a U shaped locking pin, one arm of the said pin engaging with the bolt to lock it against movement, the other arm projecting into the 95 keyhole and off center thereof, a key adapted to coöperate with the last named arm to release the first named arm from engagement with the bolt and co-operating means on the key and bolt for moving the latter 100 when the key is turned.

5. A lock comprising a bolt and a U shaped locking pin, one arm of the said pin 105 engaging with the bolt to lock it against movement, the other arm projecting into the keyhole, a key adapted to coöperate with the last named arm to release the first named arm from engagement with the bolt as the key is inserted in the lock, and ratchet teeth on the bolt coöperating with pinion teeth 110 on the key for turning the said bolt.

6. A lock comprising a bolt and a U shaped locking pin, one arm of the said pin 115 engaging with the bolt to lock it against movement, the other arm projecting into the keyhole, a key adapted to coöperate with the last named arm to release the first named arm from engagement with the bolt as the key is inserted in the lock, and ratchet teeth 120 on the bolt coöperating with pinion teeth on the key for turning the said bolt, and a pin in the keyhole slot engaging others of the pinion teeth for positioning the key as it is inserted in the lock.

In testimony whereof I affix my signature. 125
JAMES M. MCKEE.
